UNITED STATES PATENT OFFICE.

ALEXANDRE GUENETTE, OF LACHUTE MILLS, QUEBEC, CANADA.

FIRE-ALARM.

1,031,336.

Specification of Letters Patent.

Patented July 2, 1912.

Application filed May 29, 1911. Serial No. 429,969.

To all whom it may concern:

Be it known that I, ALEXANDRE GUENETTE, a subject of the King of England, residing at Lachute Mills, in the Province of Quebec, 5 Canada, have invented certain new and useful Improvements in Fire-Alarms; and I do hereby declare that the following is a full, clear, and exact description of the invention, such as will enable others skilled in the 10 art to which it appertains to make and use the same.

The invention to be hereinafter described relates to fire alarms and more particularly to electric fire alarms.

15 In order to more clearly disclose the construction, operation, and use of the invention, reference should be had to the accompanying drawings forming part of the present application.

20 Throughout the several figures of the drawings like reference characters designate the same parts.

In the drawings: Figure 1 is a top plan view of the clock work or train actuating 25 mechanism; Fig. 2 is a side elevation of the same; Fig. 3 is a right hand end elevation of Fig. 2; Fig. 4 is a view similar to Fig. 2 with the near wall of the casing removed; and Fig. 5 is a section through a building, 30 with the invention applied.

The main object of the invention is to provide a simply constructed, economical, efficient, and accurate alarm which may be equally well applied to one, or to a number, 35 of buildings or parts of buildings.

Referring to the drawings in detail, 1 indicates a suitable support or casing in which is mounted a weight actuated clock train 2. The weight 3 for actuating the train is 40 movably mounted on the outer end of a lever arm 4. The outer end of the arm 4 is fulcrumed on the arbor of the master gear of the clock train and carries the spring pressed actuating pawl 5 which co-operates with the 45 ratchet wheel 6 fixed to the master gear. Thus, when the arm 4 is drawn downward by the weight 3, the clock train will be operated, whereas, lifting of the arm will not cause operation of the clock train. Normally, 50 the weight 3 and arm 4 are held in raised or inoperative position by means of a yoke 5 pivotally connected to the casing walls and adapted to either swing under and support the weight, as in full lines, or to be 55 raised to the dotted line position to free the weight—see Fig. 2.

To effect raising of the yoke 5 to free the weight, bell crank levers 7 are provided. These levers are fulcrumed on a rod 8 mounted in the upper part of the walls of 60 the casing. Each lever is provided with an off set arm 9 adapted to engage the edge of yoke 5 and lift it to free the weight. The lever is so fulcrumed that it will swing by gravity to the dotted line position of Fig. 2. 65 However, to assist in this movement, an actuating weight 10 is adjustably mounted on the long arm of the lever. This long arm, with its weight, however, is kept normally raised by means of a chain or other device 70 11. This chain or other flexible connection is passed over suitable guide rollers and extended around the walls of a room or building near the ceiling and has its free end connected to one branch of a bell crank lever 75 12, the opposite branch of the lever being weighted to keep the chain, or the like, taut and so hold the lever 7 raised and inoperative. The chain or other connecting means is provided with a number of easily fusible 80 links or sections distributed throughout its length. As soon as any one of these links or sections is fused by fire, the lever 7 will be released and will swing to the dotted line position of Fig. 2, thus freeing the weight 3 85 and causing operation of the clock train.

Splined to the arbor of the last gear of the clock train is a contact 13. This contact is inclosed in a heavy or circular block of insulation 14 in such manner that only 90 its tip is exposed beyond the surface of the block. As the arbor rotates, the contact meets the surface of the spring contact finger 15 projecting from the inner end of a binding post 16 mounted in one wall of the 95 casing just a short distance from the arbor carrying the contact 13. A second binding post 17 is connected to the frame or casing adjacent the end of the arbor on which contact 13 is mounted. Each of the binding 100 posts receives one of the branch wires of an alarm circuit. This circuit is normally open except when contact 13 engages contact 15. At such time the circuit is closed and the alarm will be sounded. The number of times that the alarm is sounded is 105 determined by the number of revolutions of the arbor carrying contact 13. This, of course, may be regulated as desired. It should be noted that a plurality of levers 7 110 may be used, one for each building, room, or apartment to be protected. In such case,

a fire in any one of the buildings, rooms, or compartments, will operate to release that particular lever and thus close the circuit to operate the alarm.

5 It is thought that the operation and use of the invention will be clear from the preceding detailed description.

Changes may be made in the construction, arrangement, and disposition of the several 10 parts of the invention without in any way departing from the field and scope of the same and it is meant to include all such within this application wherein only a preferred form has been disclosed.

15 Having thus fully described my invention, what I claim as new and desire to secure by Letters Patent is:

1. An apparatus of the character described, comprising a normally open electric 20 alarm circuit, clock train mechanism adapted to close said circuit, a weight operated lever for actuating said clock train mechanism, a yoke adapted to support said lever in inoperative position, a bell crank lever

adapted to engage and lift said yoke to free 25 said weight operated lever, and a fusible device adapted to hold said bell crank lever in its lever supporting position.

2. An apparatus of the character described, comprising a normally open electric 30 alarm circuit, clock train mechanism adapted to close said circuit, a weight operated lever for actuating said clock train, a pivotally mounted yoke adapted to engage beneath and support said lever in inoperative 35 position, a bell crank lever provided with an off set arm adapted to engage said yoke and swing it to inoperative position, and a fusible device for holding said bell crank lever normally in its lever supporting position.

In witness whereof I have hereunto set my hand in the presence of two witnesses.

ALEXANDRE GUENETTE.
